FRONT FEED CARRIAGE FOR ACCOUNTING MACHINES

Walter A. Anderson, Bridgeport, Conn., assignor to Underwood Corporation, New York, N. Y., a corporation of Delaware

Application December 22, 1949, Serial No. 134,537

5 Claims. (Cl. 197—128)

1

This invention relates to paper holding means for accounting machines, and particularly to means for holding sheets fed from the front of the platen.

In some types of accounting it is necessary to print several horizontal lines of entries on one or more sheets while only one line is required on one or more other sheets. The customary way to perform line spacing for work of this nature is to provide a split in the platen so that the sheet or sheets requiring multiple spacing may be advanced to the exclusion of the others.

The use of a split platen structure has a disadvantage, however, in that it is not possible to use the machine for work requiring sheets wider than the individual sections of the platen.

It is an object of the invention, therefore, to provide a means for holding front fed sheets in position to receive single line entries while other entry sheets are fed from line to line for multiple line entries, without resorting to a split platen structure.

Other objects and features of the invention will be in part obvious and in part particularly pointed out in the following description of a preferred embodiment of the invention.

In the drawings:

Figure 1 is a side elevation showing the front-feed mechanism in open position.

Figure 2 is a side elevation showing the front-feed mechanism in closed position.

Figure 3 is a fragmentary plan view of parts of the paper guiding and holding mechanism.

Figure 4 is a front elevation of parts of the paper guiding and holding mechanism.

Figure 5 is a fragmentary sectional side view directed to a modified form of the front-feed sheet holding means.

Figure 6 is a schematic front view showing feed-rolls for a right front-fed sheet incapacitated, and showing such sheet immovably held between companion holding elements, while a left front-fed sheet is pressed against the platen for line-feeding movement thereby.

Figure 7 is a fragmentary sectional side view directed to the feature shown in Figure 6, and showing the companion holding elements in their open position, for receiving a front-fed sheet.

Figure 8 is a view similar to Figure 7, but showing the companion holding elements in sheet holding position.

Figure 9 shows in side elevation one of the lower clipping elements about to be applied to its support on the carriage.

Figure 10 is a plan view of a pair of companion

2

holding elements together with their related parts, and

Figure 11 is a perspective view of rear feed-roll as used in the modification of Figure 5.

5 This invention is a continuation in part of my copending application Serial No. 679,722, filed June 27, 1946, now Patent No. 2,536,524, dated January 2, 1951, to which reference may be had for a more complete disclosure of the machine to which the present structure is more particularly adapted.

10 Referring to Figure 6, the machine is adapted to accommodate rear fed sheets such as R and front fed sheets such as S. The sheets are introduced around a cylindrical platen 7 of the conventional type.

15 Feed-rolls 134, Figures 2 and 7, bear normally upon the rear side of the platen 7, below the level of the platen shaft 112, and other feed-rolls 135 bear normally upon the top side of the platen, all to hold a record sheet R in typing position on the platen. Above the feed-rolls 134, and inclined rearwardly, is a sheet supporting table 136, Figure 2, rigidly fastened between the carriage ends. The record sheets R are rear-fed to the platen, downwardly in front of said table 136, and are rolled between said feed-rolls 134 and the platen, forwardly and upwardly, by turning the platen 7, the leading end of the sheet being directed underneath the top feed-rolls 135.

20 The bottom feed-rolls 134, of which there are a series extending along the platen, are each rotatively supported at opposite ends by levers 156, upon a common pivot rod 157 carried on a generally Z shaped supporting web 158 which extends the full length of the carriage and is rigidly carried thereon. Springs 160 urge the individual feed-roll supporting levers 156 toward the platen. A flat-faced cam shaft 161 is provided to

25 act, when turned, upon upreaching arms of the levers 156, to displace them forwardly and cast the feed-rolls 134 a small distance away from the platen 7. Said shaft 161 is rotatable to throw off the feed-rolls 134 by operation of a suitable finger piece (not shown).

30 The feed-roll supporting levers 156 have tapered tongues 163 reaching forwardly of the feed-rolls 134 and slightly spaced from the platen, such tongues guiding rear-fed sheets such as record sheet R, in a curved path toward the front of the machine. The rear-fed sheets as they emerge at the front of the platen are manually directed rearwardly under the top feed-rolls 135, these rolls, if desired, being temporarily released for the purpose. In practice, a

35 record sheet R is presented to the machine next

to the platen while the previously finished record sheet is still in place, such latter sheet being used to guide the newly introduced sheet around the platen and underneath the rolls 135.

Front-feed table and throat

The invention provides for convenient front-feeding of work sheets, such as said statement sheets S, down the front side of the platen and thereunder to the rear. Figure 2 shows a statement sheet S in position for typing thereon, paper holding means in the form of feed-rolls 168, being shown bearing against the lower front side of the platen 7 to hold such sheet. Above the typing line 13, a front-feed guide or table 170, preferably of transparent material, bears rearwardly against the statement sheet S, thereby causing the latter to be wrapped in close contact around the front side of the platen 7 at the typing line 13, suitably for receiving impressions from the type bars. With the front-feed table 170 in the position shown in Figure 2, the usual type bars 14, Figure 1, can rise freely for typing impressions. As illustrated in Figure 1, in order to facilitate removal and insertion of the statement sheets S, feed-rolls 168 are cast off the platen and the front-feed table 170 is displaced forwardly. It will be seen from Figure 1 that the statement sheet S, in the shown position of the table 170 and the feed-rolls 168, is freely removable, and that another such sheet can be conveniently and freely inserted down the rear of the table 170 into the feed-throat formed between the platen 7 and the cast-off rolls 168.

The transparent front-feed table 170 is co-extensive in length with the platen, and is secured along its upper margin to a bar 171. The bar 171 is carried on opposite ends of the carriage by plates 173 which are pivoted to the adjacent side walls of the carriage by pivot studs 174 located preferably to render the front-feed table 170 displaceable about an axis that lies parallel to the platen 7 and to the rear and below the platen axis. This provides that during the restoration of the table 170 its lower edge will glide upwardly over the front-fed paper to wrap it in taut contact with the platen.

Said feed-rolls 168 extend in a row along the platen and each is rotatively supported at the opposite ends thereof by arms 175 carried swingably upon a supporting shaft 176. Brackets 178 flank each pair of opposite feed-roll carrying arms 175 and are fastened behind the shaft 176 as at 179, to the rail bar 113 of the carriage, and are fastened forward of said shaft to a carriage-frame-bar 181 which extends parallel to the platen and spans the space between the carriage end-walls. Said brackets 178 carry the shaft 176 extending therethrough to afford bearing supports for the latter. Springs 177 attached to rearward extensions of the arms 175, and anchored to the adjacent brackets 178 urge said arms 175, and thus the feed-rolls 168, constantly towards the platen 7. The shaft 176 has a flat surface that carries intermediate each pair of feed-roll carrying arms 175 an element 182. Each of these elements 182 has opposite, apertured ears 183, Figure 3, to fit the shaft 176 and to turn therewith, the spaced ears in conjunction with the brackets 178 serving to locate the feed-roll arms 175 properly spaced along the shaft 176. Said elements 182 reach under the aforesaid feed-roll arm extensions, and are normally slightly spaced therefrom to allow good feeding contact of the rolls 168. To release the

feed-rolls 168, the shaft 176 is given a counter-clockwise movement as shown in Figures 1 and 7, so that the elements 182 thereon will engage and move the feed-roll arms 175 to cast off the rolls 168.

The mechanism to open and close the front-feed throat as fully described in the parent application No. 679,722 mentioned above will be briefly described herein.

- 10 Referring to Figure 1, shaft 176 carries at one end an upstanding arm 25 slotted as at 28 at its upper end. A slide 27 slidable on screws 28 fixed in the carriage end carries a stud 29 on its forward end, the stud 29 resting in slot 26 of arm 25. Slide 27 is urged rearwardly by a spring 30 connected between the slide and a stationary part of the carriage. Slide 29 may be moved forward to open the throat by a handle (not shown) secured at 31 to the slide or by a power operated bail (not shown) connected to the slide at 32.

Slide 27 is retained in its forward position by a latch arm 35 pivoted on a stud 36 in the carriage, the latch 35 having a lug 37 which will in the forward position of slide 27 drop behind a projection 38 of slide 27 to retain the throat open as in Figure 1. Latch arm 35 has a slot 34 in its rearward end to embrace a fixed stud 39 to limit the movement of the latch arm. The latch may be released automatically at the start of a machine cycle by a power-operated bail (not herein shown) connected to a depending arm 40 of the latch 35 or manually by a key 41 on the carriage. Key 41 is fixed to the forward end 30 of a lever 42 pivoted on a stud 43 on the carriage and urged clockwise by a spring 44 between the lever 42 and the carriage. The rearward arm of lever 42 underlies an ear 45 bent off of latch arm 35 to raise the arm 35 to releasing position upon depression of key 41.

Slide 27 also moves the front feed table 170 to open throat position. A link 50 secured by a screw 51 to arm 173 of the table 170 is slidably carried at its rear end on stud 39 and has a lug 52 bent off to rest in front of a stud 53 secured in slide 27. Thus the forward movement of slide 27 will move the front feed table 170 to open throat position at the same time that the feed rollers 168 are cast off. A spring 54 connected between upstanding lugs on the rear ends of link 50 and slide 27 serves to yieldingly return table 170 to closed throat position when slide 27 is released.

The sheets S which are front-fed down between the platen 7 and feed-rolls 168, see Figure 7, take a wide sweep around the underside of the platen, rearwardly well below the tapered tongues 163 of the rear feed-rolls 134. Such wide sweep is given the sheets by guiding elements 185, see also Figure 3, situated between the feed-rolls 168, and below which the latter withdraw when released. The said guiding elements 185 are augmented in their function by a paper shelf 186, see Figure 3, which has only a slight upward tilt to the rear and which extends the full distance between the opposite carriage ends 111. The wide and gradually curved channel provided facilitates introduction of all commonly used weights of paper without material tendency to buckle; yet the bend given the work-sheets produces enough friction to cause them to remain in position upon introduction. Said paper shelf is fastened at the rear to a square bar 187 fast on the carriage, and ends at the front in spaced sections 184 having vertically bent tabs 184a for securing the sec-

tions 184 to the square bar 181 by shouldered screws 188, see Figures 2 and 4. The said guiding elements 185, see Figures 3 and 4, are situated between the gaps 191 formed between the sections 184 and are laterally intermediate the feed-rolls 168. They, as seen in Figures 2 and 3, are formed at the rear with upwardly and downwardly offset tines 190 to clip onto the paper shelf 186, and at the front they each have a sharp angular bend, downwardly and rearwardly for attachment to the front of the bar 181 by screws 189, as shown also in Figure 4.

The feed-rolls 168 are withdrawn slightly below the guiding elements 185, but because the work-sheets S in being front-fed have a tendency to flex downwardly between said guiding elements 185, they tend to get caught or fouled on the front sections 184 of the paper shelf 186. Moreover, they also tend to contact with the feed-rolls 168, the latter of which if contacted obviously offer considerable resistance. Work sheets which are of light weight, and/or notched or punched along the introductory edge, as for accommodation into binders or files, are particularly subject to the above tendencies, but even straight-cut work sheets when their edges become curled, nicked or torn, as from repeated handling, will tend to be troublesome. Provision is therefore made to assure, in all cases, smooth, substantially resistless guidance of front-fed work-sheets S rearwardly underneath the platen and onto the paper shelf. Drawing attention especially to Figures 3 and 4, to this end there is accommodated at a circumferentially reduced, intermediate section 168a of each feed-roll 168, a deflector element 192, each such element having a narrow sheet-deflection shelf 192a positioned close to the platen 7 when said feed-rolls 168 are in applied position, but moved an appreciable distance from the platen when the feed-rolls are cast off, that is when the carriage is conditioned for front-feeding work-sheets as seen in Figure 1. The deflector shelves 192a move downwardly a lesser distance than the feed-rolls 168, and in fact said shelves 192a will lie slightly above these feed-rolls and will thus guide the paper with some clearance over the rolls. The deflector elements, see Figures 1 to 4, are formed of narrow strips of sheet metal and comprise each a main vertical leaf 193 which at the top has a four-sided cage bent therefrom, in which is accommodated the reduced feed-roll section 168a. A top side of said cage consists of said deflector shelf 192a, and another side 192b underlies directly the reduced feed-roll section 168a. Each of the deflector elements 192 has a vertical slot in the vertical portion 193 thereof, and the screws 188 which fasten the front-end of the paper-shelf to the bar 181, are shouldered to provide guides and mount the various deflector elements 192 for vertical sliding movement. To keep said elements 192 in straight position they have each at the bottom-end thereof, a lug 193a piloted in a vertical slot 194a provided in a plate 194 overlying one of the bent-down tabs 184a of the paper-shelf 186, said plates 194 and tabs 184a being firmly clamped to the bar 181 by the shoulders of said screws 188. Preferably the vertical leaf 193 is slightly bowed to enable the screw 188 to keep the element 192 frictionally in whatever position it is moved to, and to prevent rattling thereof. In operation, when the feed-rolls 168 are being applied, the reduced sections 168a thereof contact the shelf 192a within said cage to lift the deflectors 192 upwardly to the position 75

seen in Figure 2. During the release of said feed-rolls 168, the deflector elements 192 will be given a downward movement by engagement of the reduced feed-roll sections 168a with the lower wall 192b of said cage, but such downward movement will commence only after the feed-rolls have withdrawn below the deflector shelves 192a, the final relative positions of the parts being as illustrated in Figure 1, affording smooth guidance to front-fed sheets over the rolls 168, and without any possibility of the sheet S becoming fouled.

Provision for line-feed of one sheet independently of others

Some methods of keeping records require use of several laterally spaced front-fed sheets only one of which sheets is to be given a line-spacing movement. Where such operation is required, the line-spaceable sheet S usually receives a group of successive entries on successive lines, subsequent to which the quiescent sheet or sheets will receive total or balance entries on a single line with respect to said group of entries, the quiescent sheet then requiring removal. Before this invention it was customary to employ split or sectional platens to take care of this type of requirement. The platens had to be split at many different locations to suit the forms of the individual customers and it was necessary to build these machines to special order, which raised the cost of the machines. The invention eliminates the use of a split platen for such work, and having now special reference to Figures 6 to 10, a front-fed sheet S required to remain stationary 20 is adapted to be gripped between companion clamp elements afforded by the tongues 163 extending forwardly from the feed-rolls 134 and one or more clamp leaves 361 hingedly movable upwardly for clamping action against said tongues. Said clamp leaves are attachable wherever required between the sheet-guiding elements 185 which underlie the platen, said elements 185 having pintles 362 extending oppositely therefrom at their folded forward ends, and 25 the clamp leaves 361 being formed with socket-forming ears 363 for ready attachment to the pintles 362. The rear feed-rolls 134 and their supports 156 are arranged symmetrically behind the front feed-rolls 168 as depicted in Figure 10. The clamp leaves 361 are applied to the pintles along that portion of the platen where a front-fed sheet S is required to be held during line-spacing operations as in Figure 6 where they are applied along the space where the right hand sheet S is situated. The clamp leaves 361 directly overlie the feed-rolls 168. Whenever the front-feed device is conditioned for front-feeding, and the feed-rolls 168 are thus released, said leaves, as seen in Figure 7, are out of contact 30 with said tongues 163 and afford a wide-open front-feed path. Whenever the machine is operated for restoration of the front-feed device, as described hereinbefore, the feed-rolls 168 will be urged to rise under tension of the springs 177, but wherever clamp leaves 361 overlie such feed-rolls, the latter will force the leaves resiliently upwardly into clamping engagement with said tongues 163, for holding the front-fed work-sheet independently of the platen, as seen in 35 Figures 6 and 8. Moreover, such feed-rolls 168 as are underlying the clamp leaves 361, are prevented from rising into contact with the platen, but all the other such rolls will rise as is diagrammatically illustrated in Figure 6, wherein the left sheet S is clamped against the platen and 40

wherein the sheet S to the right is held independently thereof. Viewing Figure 6, it will thus be evident that line-spacing motion imparted to the platen will line-space the left front-fed sheet S but not the sheet S at the right. The clamping elements 361 have clearances 364, see Figure 10, for accommodation of the deflector elements 192.

Use of the clamping leaves is not restricted to the feeding of one front-fed sheet to the exclusion of another, but, obviously, a front-fed sheet may be held stationary by clamp leaves 361 while a record sheet R may be given movements independently thereof.

It is at times desirable to print data on front-feed sheets closer to the bottom margin thereof than the use of clamping leaves 361 will permit. The modified form of Figures 5 and 11 may be used at such times although some decrease in flexibility is thereby introduced. This modified structure will enable front-feed sheets S to be gripped directly by the front-feed rollers 168 and consists of a plate 70 secured to the arms 158 forward of feed roller 134. Plate 70 is slightly curved longitudinally and is provided with a pair of upstanding pierced ears 71. These ears 71 are riveted to arms 158 of the rear feed-rolls 134 so that the plate 70 is clear of the record sheet R and is between the platen 7 and the feed-rolls 168.

A front-fed sheet S will then be firmly gripped between the rolls 168 and the bottom of plate 70 when the shaft 176 is released prior to machine operation. Such point of contact will be farther forward than when the clamping leaves 361 are used and printing can be done closer to the bottom margin of sheet S.

The foregoing description of a preferred embodiment is illustrative only and is not to be taken as limiting the scope of the following claims for many changes and modifications are possible without departure from the scope of the invention.

What is claimed is:

1. In a business machine, a platen roller, a series of feed-rolls bearing against the underside of the platen, means to support said feed-rolls, comprising arms wherein the feed-rolls turn, said arms being supported at the rear of the rolls and being tapered closely to the platen in front of the feed-rolls, and a series of sheet-clamping elements engageable with said arms, means for resiliently pressing said clamping elements individually into engagement with said arms, and means operable to effect release of said clamping elements.

2. In a business machine, a platen roller, a series of feed-rolls engageable with the front-bottom side of the platen to feed a work-sheet when the platen is turned, means resiliently urging said feed-rolls towards the platen, means oppositely operable to cast said feed-rolls an appreciable distance from the platen or to allow said urging means to cast them on, surface pre-

senting means to the rear of the feed-rolls, below the platen and facing away therefrom, means applicable to overlie at least some of said feed-rolls, and, when applied, being movable upwardly into and downwardly away from engagement with said surface means, respectively to clamp and release a work-sheet, and means to move said applicable means into and out of contact with said surface presenting means incident to opposite operation of said operable means.

3. In a business machine, a platen roller, feed-roll means adapted for cooperation with the platen for holding and line-feeding a work-sheet, a series of feed-rolls arranged at the bottom side of the platen for movement into and out of feeding contact with the platen, stationary surface presenting means to the rear of at least some of said feed-rolls, facing away from the platen, clamping units, and means to render said units readily applicable to overlie and incapacitate the individual feed-rolls and to underlie the surface presenting means, and for movement respectively upwardly and downwardly into sheet-clamping and sheet-releasing relations with said surface presenting means.

4. In a business machine, a platen roller, paper feed means including a first series of feed rolls engageable with the platen roller for holding and line spacing one work sheet, and members supporting said first series of feed-rolls, a second series of feed rolls below said platen roller for engagement therewith to retain and line space a second front-fed work sheet, engaging and disengaging means for said second series of feed rolls and a plurality of detachable clips overlying certain of said second series of feed rolls and movable thereby into engagement with said supporting members of said first series of feed rolls to retain a front fed work sheet against line space movement by said platen.

5. In a business machine, a carriage, a work sheet supporting platen roller in said carriage, line space feed rolls engageable therewith to enable feeding movement of a work sheet by said platen, throat opening means to move said feed rolls from said platen to permit front insertion of the work sheet, and a plurality of members insertable between said feed rolls and said platen and in the closed position of said throat engaging said feed rolls and a non-rotatable portion of said carriage to form a non-line spacing front feed throat.
